US00D956686S

(12) **United States Design Patent** (10) **Patent No.:** **US D956,686 S**
DiLella (45) **Date of Patent:** **** Jul. 5, 2022**

(54) **BATTERY PACK**

(71) Applicant: **mophie inc.**, Irvine, CA (US)
(72) Inventor: **Mark Stephen DiLella**, Irvine, CA (US)
(73) Assignee: **mophie inc.**, Irvine, CA (US)
(**) Term: **15 Years**
(21) Appl. No.: **29/794,868**
(22) Filed: **Jun. 15, 2021**

Related U.S. Application Data

(62) Division of application No. 29/675,990, filed on Jan. 7, 2019, now Pat. No. Des. 940,647.

(57) **CLAIM**

The ornamental design for a battery pack, as shown and described.

DESCRIPTION

FIG. 1 is a front, top, and left perspective view of a first embodiment of the design for a battery pack.

FIG. 2 is a back, bottom, and right perspective view thereof.

FIG. 3 is a front elevation view thereof.

FIG. 4 is a back elevation view thereof.

FIG. 5 is a right side elevation view thereof.

FIG. 6 is a left side elevation view thereof.

FIG. 7 is a top plan view thereof.

FIG. 8 is a bottom plan view thereof.

FIG. 9 is a front, top, and left perspective view of a second embodiment of the design for a battery pack.

FIG. 10 is a back, bottom, and right perspective view thereof.

FIG. 11 is a front elevation view thereof.

FIG. 12 is a back elevation view thereof.

FIG. 13 is a right side elevation view thereof.

FIG. 14 is a left side elevation view thereof.

FIG. 15 is a top plan view thereof; and,

FIG. 16 is a bottom plan view thereof.

The broken lines in the drawings depict portions that form no part of the claimed design.

1 Claim, 12 Drawing Sheets
